United States Patent Office.

THOMAS DOLAN, OF PHILADELPHIA, PENNSYLVANIA.

Design No. 3,965, dated April 12, 1870.

DESIGN FOR STOCKING FABRIC.

The Schedule referred to in these Letters Patent and making part of the same

I, THOMAS DOLAN, of Philadelphia, county of Philadelphia, State of Pennsylvania, have invented or produced a Design for a Stocking Fabric, of which the following is a specification.

The figure in the accompanying drawing represents sufficient of a stocking fabric to illustrate my design, the main features of which consist of the two stripes A A, each consisting of a central vertical row of diamond-shaped spots, a, between two rows, b b, of similarly-shaped spots, the rows being separated by zigzag lines, as shown in the drawing, and the stripes being bounded on each side by a zigzag edging, e.

Between the main stripes A A is a smaller stripe, B, and the fabric is edged with a pattern, h, the two patterns forming together, when the edges of the fabric are united, a stripe of a character similar to that of the stripe B.

Claim.

The design for a stocking fabric, substantially as described, and as illustrated in and by the accompanying drawing.

In testimony whereof I have signed my name to this specification in the presence of two subscribing witnesses.

THOMAS DOLAN.
